COLLATOR

Nils G. Hernblad, Long Island City, N. Y., assignor
to American Type Founders, Inc., a corporation
of New Jersey

Application April 18, 1947, Serial No. 742,328

12 Claims. (Cl. 270—58)

1

This invention relates to collators and primarily to devices of this type designed and intended to be used in business offices for the grouping of sheets.

Machines for collating sheets have heretofore been designed, suggested and placed in use but, for the most part, such machines have been of a rather complicated design and have furthermore been generally of such character that they frequently ceased to function satisfactorily after relatively short periods of use or were unable to function satisfactorily in collating sheets of certain grades, types and weights of paper.

It is well known to those engaged in the manufacture and operation of machines for feeding sheets that it is a difficult matter to feed certain types of sheets under any conditions and also that sheets which may be fed without difficulty under favorable conditions may be fed only with difficulty or not at all under unfavorable conditions. Sheets of certain grades may be fed satisfactorily from a pile prior to printing but fed only with difficulty after they have been printed. The feeding of certain types of sheets may be rendered most difficult by unfavorable changes in atmospheric conditions and the presence of electric charges commonly known as static. A collator to be effective must, of course, be operative with all grades of paper under all operating conditions and one reason why machines of this type have not heretofore been widely used, and hand collating is still largely practiced, is because of the fact that such machines as have heretofore been employed have not operated satisfactorily under all working conditions.

The object of the present invention is to provide a collating machine of simple character, which is compact, may be fabricated at low cost, is durable, and which will effectively feed and operate under all ordinary working conditions. The leading edges of the various sheets which are simultaneously fed at a single operation of the machine are brought together, or approximately together, at a station readily accessible to the operator of the machine and in such manner that the operator may simultaneously grasp all of the sheets thus fed. It has heretofore been suggested that guide means may be employed for guiding to a common grasping station the leading edges of a series of sheets simultaneously fed from a plurality of piles to a common point or station. By such a means sheets fed from a plurality of piles disposed in a vertical series of piles may be guided to the point at which they are to be grasped, but it sometimes occurs that, in the feeding of light sheets under certain conditions,

2

the movements of the sheets along a sheet guide is impeded or prevented because of static and in other instances sliding movement of the sheets upon each other causes them to cling together. One objective of the present invention is to provide an improved means for insuring that the leading edges of all of the sheets of a series simultaneously fed from a plurality of piles will definitely reach a point or station at which they may be conveniently grasped by the operator, which means is not subject to the objections which have been heretofore directed against earlier machines of this general type.

The vertical series of pile supporting members, 15 if there are a substantial number in the series, as for instance, eight, may be divided into two groups, an upper group and a lower group. The leading edges of sheets delivered simultaneously from the upper group may be received upon a table and the table may then be moved forwardly with the sheets to the grasping station. The sheets of the lower group of piles may be received upon a table as they are simultaneously fed forward and hence drop downwardly under their own 20 weight and, at or about the end of the feeding movement, this rocking or tilting table may be actuated to rotate about an axis and to lift the leading edges of the sheets which have been deposited upon it to the grasping station. Either 25 or both of these devices may be employed and, when both are employed, the leading edges of all the sheets simultaneously fed from a substantial number of piles arranged in a vertical series may be precisely fed to the grasping station, quite regardless of the nature and condition of the sheets and the operating conditions which exist.

The invention embodies a number of features of entirely novel and distinctive character, including an improved sheet feeding device having 40 rubber or composition sheet gripping elements of novel formation, readily attachable and hence readily replaceable when they become smooth, hard or otherwise ineffective. Novel means is provided for rendering the sheet feeding device 45 associated with any particular pile support inoperative in order that the sheet gripping element shall not engage and slide back and forth upon the stationary sheet support when no sheets are present. Other novel features will be apparent. 50 In the accompanying drawings a preferred embodiment of the invention is illustrated and this embodiment will be described in detail. It will be understood that the invention is not limited to that form thereof which has been set forth by 55 way of example but that, in adapting the same to the feeding of papers of various types and

size, numerous changes in the arrangement and design of its component elements may be effected.

In the drawings:

Figure 1 is a side elevation of the apparatus, the protective and ornamental casing not being shown in order that the elements of the mechanism which are normally hidden may be clearly perceived, and portion of the mechanism being broken away for the same reason;

Figure 2 is a similar view but showing the operating parts of the machine in different positions;

Figure 3 is a view of the machine from the front, certain elements thereof having been removed in order that others may be more clearly observed;

Figure 4 is a section on line 4—4 of Figure 1;

Figure 5 is a top plan view of a carriage forming portion of the operating mechanism;

Figures 6 and 7 are side and top plan views respectively of a preferred form of sheet feeding device;

Figure 8 is a perspective view of portion of such sheet feeding device;

Figure 9 is a fragmentary view of several of the paper pile supporting members, with means for maintaining the associated pusher elements in inoperative position; and

Figure 10 is a section on line 10—10 of Figure 9.

The frame of the collator shown in the drawings comprises four principal upright members or legs, indicated at 10, connected by suitable bracing members to render the structure stable. The upper ends of the four corner members or legs 10 are secured to parallel horizontally extending frame members 11. Supported upon the parallel members 11 are the four corner pieces 12, 13, 14 and 15 of the upper portion of the apparatus, and suitably secured to these four uprights, as by screws or by welding, are the several pile supporting platforms of a vertical series of horizontally disposed pile supporting platforms 17 upon which, respectively, may be placed piles of sheets to be collated, a series of such piles for instance being indicated at P to P⁷ in Figure 1 of the drawings. The piles P, P¹, P² and P³, which are the uppermost four piles of the series of eight piles, may be designated piles of the upper group and the lower group of piles comprises piles P⁴, P⁵, P⁶ and P⁷. These piles may be positioned either by inserting them from the front or from the rear of the machine, the ends of the pile receiving bins being always open at the front and also open at the rear unless closed by a cover sheet or casing.

Positioned above each of the pile supports so as to be movable along a path parallel to the top sheet of each pile is a sheet feeding device, these devices being indicated at S, S¹, S², S³, S⁴, S⁵, S⁶ and S⁷. Each comprises a metallic member such as that shown in detail in Figures 6, 7 and 8. The elongated, forwardly extending main portion 20 of each sheet feeding device has transversely extending integral webs 21 at its rear end, terminating in downturned flanges or ears 22, these ears 22 being provided, respectively, with aligned circular openings 23. Extending laterally from member 20 adjacent its forward end, in opposite directions, are arms 24 and 25, the ends of which are slotted as at 26. Rubber or composition sheet engaging and gripping elements are indicated at 27. Each of these comprises a lower portion 28 having a rounded sheet engaging undersurface, an upper portion 29, and

an intermediate rib 30 connecting portion 29 to the sheet engaging portion 28, the width of the rib being substantially the same as the width of the slot 26 in the associated arm of the feeding device. A gripping element 27 may be readily assembled with one of the sheet feeding devices by inserting the end of rib 30 in one of the slots 26 and sliding the gripping element longitudinally of the arm of the feeding element until it reaches the position in which it is shown in Figure 8. When one of the gripping elements 27 becomes smooth or worn, hard or otherwise defective, it may be quickly removed and replaced by a new element. As these are the only elements which may wear or deteriorate over a long period of time, the collator may be very easily kept in serviceable condition.

Each of the feeding devices is operatively connected to means for moving it horizontally and longitudinally of the bin in which it is located on its sheet feeding and return strokes. From an inspection of Figures 1, 3 and 4 it will be observed that the rear end of each such device is mounted upon a horizontally disposed rod, the several rods being indicated at R, R¹, R², R³, R⁴, R⁵, R⁶ and R⁷, each rod passing through the aligned apertures 23 of the associated feeding device and each such device being therefore supported at its rear end in such manner as to be free to rotate about its support so that the principal portion of the weight of the feeding device, including the two sheet gripping elements 27 associated therewith, rests upon the top sheet of the pile over which the feeding device is to work in the operation of the machine.

As the height of each pile decreases in the operation of the machine, the sheet gripping elements of devices S, S¹, S², S³, S⁴, S⁵, S⁶ and S⁷ descend correspondingly each being at all times in engagement with the top sheet of the pile below. The ends of the several rods R, R¹, R², R³, R⁴, R⁵, R⁶ and R⁷ are mounted in a reciprocating frame which includes the parallel vertically disposed upright members 33. The upper ends of these members are connected by the cross rod 34 and the lower ends are attached as by screws 35 to a carriage generally indicated at C. This carriage may be most clearly observed in Figure 5 and is seen to comprise a generally rectilinear frame which includes the U-shaped member 36 and the connecting cross member 37.

Studs 38 extending outwardly from the parallel legs or side members of the U-shaped part 36 support rollers 39 and two of the series of four rollers 39 rest upon each horizontal supporting rail 40 which are disposed in parallel relation and the ends of which are connected, respectively, to the upright legs 10 of the frame. Disposed above, and parallel to the supporting rails 40, are the guard or confining rails 41, which prevent dislodgment of the rollers and displacement of the carriage C. The means for limiting the movements of the carriage includes the rubber cushioning members indicated at 42 and 43, respectively, which are positioned to strike the rear flanges of angle members 10 when the carriage is at the end of its rearward travel. The free ends of the U-shaped member 36 contact the forward legs 10 to limit the forward travel of the carriage, as indicated in dotted lines in Figure 5. To the downwardly extending and laterally offset terminal ends of the upright members 33 of the reciprocating frame are connected the ends of links 45 and the opposite ends of these links are connected to the upper ends of the parallel legs

of a U-shaped lever 46, the legs of this lever being pivotally mounted upon the short studs 47 supported in the transverse horizontally extending frame members 48 of the machine. The lever is thus mounted for rocking movement about a horizontal axis. The lower ends of the legs of lever 46 are connected by a foot or treadle bar 50. A coiled tension spring 51 acts upon lever 46 at all times and normally draws this lever into the position in which it is shown in Figure 1, so that the carriage C is in its rearmost position, likewise the reciprocating frame mounted upon the carriage and upon which the ends of the sheet feeding element supporting bars R, R¹, R², R³, R⁴, R⁵, R⁶ and R⁷ are mounted. Obviously, when the operator presses his foot against the cross bar 50 and moves this bar rearwardly the spring 51 will be extended and the lever 46 will be rocked from the position in which it is shown in Figure 1 to the position in which it is shown in Figure 2, the reciprocating frame 33 will be moved forwardly and the several sheet feeding devices will be simultaneously actuated, moving to the positions in which they are shown in Figure 2.

The operation which has just been described is a sheet feeding operation and as a result of this operation the top sheet of each pile will be fed forwardly and out of the housing which contains the vertical series of piles. If the leading ends of the sheets are then grasped by the operator all of them may be readily and completely withdrawn, whereupon the sheet gripping elements 27 will descend, respectively, and engage the next uppermost sheets of the several piles. The operator will then release the treadle bar 50 and spring 51 will withdraw the reciprocating frame to its rearmost position, effecting the simultaneous retraction of all of the sheet feeding devices and restoring them to initial position.

In Figure 2 of the drawings all of the sheet feeding devices are shown in the positions which they occupy at the ends of their feeding strokes and the leading ends of the sheets which have just been projected by the feeding mechanism are shown to be collected or gathered together at what may be designated a collecting station, generally indicated at T, so that they may all be readily grasped by the operator of the machine. It will be seen that the leading ends of the four uppermost sheets are supported upon a member which may be designated a reciprocating table and which is indicated by the numeral 55. The leading ends of the four sheets of the lowermost group of sheets are shown to be resting upon a member 56, which may be designated a rocking table. The reciprocating table 55 moves between the positions in which it is shown in Figures 1 and 2 and derives its reciprocatory motion from the reciprocating frame 33, the ends of table 55 being mounted upon horizontally extending members 57, the rear ends of which are connected to the frame 33 by lost motion connections each comprising a pin affixed to the reciprocating frame, which pin may be the projecting end of bar R⁴ and which works in a slot 59 formed in member 57. The lower edges of the horizontally extending members 57 rest upon rollers 60 so that these members are maintained in horizontal positions at all times but may be freely reciprocated longitudinally.

By reason of the lost motion connection between members 57 and the reciprocating frame 33, the table 55 will remain in retracted position as shown in Figure 1, until the leading edges of

the upper group of sheets to be fed have been partially projected and have dropped downwardly toward or upon the table below. Thereupon the table 55 moves with the leading edges of the sheets and these ends will be supported thereby and carried to the gathering position T.

The rocking table 56 will remain in the horizontal position in which it is shown in Figure 1 until about the end of the feeding movement of the frame and feeding device, whereupon this table, upon which the leading ends of the sheets of the lowermost series of sheets have been deposited, will be rocked or tilted upwardly. Upon completion of this tilting or upward rocking of the table the ends of the sheets of the lower group will also be positioned in the gathering or grasping zone T. The mechanism for effecting this tilting or rocking of the table 56 is of simple character and comprises a pusher element 62 extending forwardly from the carriage C, which element 62 is adapted to strike the downturned flange 63 of the rocking table 56 and to cause this table to tilt upwardly about the axis of the horizontally disposed supporting rod 64, upon which it is mounted. It will be observed from an inspection of Figure 3 that rod 64 has its ends supported in the frame of the machine and passes through blocks 65 affixed to the downturned flange portion 63 of table 56.

One end of rod 64 is provided with a knob 64a by means of which it may be conveniently grasped by the hand and moved longitudinally (toward the right in Figure 3) against the action of spring 66 which encircles the rod. By such movement 30 notch 63a formed in flange 63 of the tilting platform may be brought into alignment with pusher 62 mounted on carriage C, thus permitting the carriage to be moved forwardly without actuating the tilting plate or table. An attendant can 35 then easily insert fresh piles of paper in the several compartments, the feeding devices being easily accessible and the tilting table being out of the way.

It will be observed from an inspection of Figure 5 that the pusher element 62 is mounted upon the forward end of a rod 68. Rod 68 extends through aligned apertures formed in the parallel transversely extending members of the carriage and is slidable relatively to the carriage in these apertures. A helical compression spring 69 encircling the rod has one end bearing upon the carriage and the other end upon an annular member 70 adjustably secured to rod 68 by a set screw. The action of spring 69 may be varied by adjusting abutment 70 longitudinally of rod 55 68. The forward position of the pusher element 62 may be determined by an adjusting stop member 72 along the length of the rod, forward movement of the rod and pusher element under the influence of spring 69 being terminated by contact of member 72 against the transverse member 37 of the carriage.

It will be observed from an inspection of Figures 1 and 2 that the forward ends of the pile supporting members are equidistantly spaced from the gathering station T or, in other words, the gathering station T comprises the axis of a theoretical cylinder of which the leading edges of sheets resting in the respective piles comprise elements. Each leading edge, therefore, travels an equal distance from its position in the pile to the gathering position and these edges, therefore, upon reaching that position, are in substantial registry.

The operator of the machine can therefore

hardly fail to grasp the leading edges of all sheets for each operation of the machine and the set of sheets which is transferred to the jogging machine will be complete. If no jogging machine is available to secure a perfect registration of the set thus withdrawn, these sheets may be readily placed in complete registration manually by the operator who will simply tap the corresponding lower edges of the sheets of the set upon the table member 56 when that member is in its lowermost position, as shown in Figure 1. The feeding of a set of sheets from the machine can be accomplished quickly and certainly by simply pressing against the foot bar or treadle and, for reasons previously set forth, the leading edges are brought certainly and accurately to the grasping zone regardless of the nature of the paper being fed or the atmospheric or other conditions which may exist in the space in which the machine is located.

The machine may of course be used in the collation of two or more sheets at each operation, or a larger number, up to its capacity. If less than the maximum number of sheets are to be fed certain of the feeding devices should be rendered inoperative in order that the sheet gripping elements may not be unduly worn by rubbing directly against the metallic sheet supporting shelves over which they move. This may be accomplished by the means illustrated in Figures 9 and 10. As shown in these figures a sheet feeding device may be rendered inoperative by inserting into the bin in which it is located a member 80, preferably of sheet metal and having an elongated vertically disposed blade like main portion 80a and a horizontal minor portion or base 80b, portion 80b having integral therewith a flange 80c. The forward margin of a pile supporting plate may thus be clamped between parts 80b and 80c and the device maintained in the position in which it is shown.

When so positioned a transverse arm 24 or 25 of the feeding element will rest and slide upon the horizontal upper edge of part 80a and the rubber gripping elements maintained out of contact with any stationary part as the machine operates. The member 80 may also be used to laterally confine a pile of sheets, the blade like portion 80a being disposed to one side of the sheet feeding element.

Having thus described the invention, what is claimed as new and desired to be secured by Letters Patent is:

1. In a collator, in combination, a plurality of superposed supports each adapted to support a pile of sheets, means for simultaneously feeding, in a common direction, a sheet from each of such piles, and mechanism for supporting the superposed leading edges of a plurality of such sheets while such sheets are being fed, said mechanism including a member disposed below said pile supports upon which the leading ends of the advancing sheets may rest, and means for advancing said member in sheet feeding direction and thereafter returning the same to initial position preparatory to a second sheet feeding operation.

2. In a collator, in combination, a plurality of superposed supports each adapted to support a pile of sheets, means for simultaneously feeding, in a common direction, a sheet from each of such piles, and mechanism for supporting the superposed leading edges of a plurality of such sheets while such sheets are being fed, said mechanism including a member disposed below

said pile supports upon which the leading ends of the advancing sheets may rest, and means for advancing and retracting said member along a predetermined path of movement.

3. In a collator, in combination, a plurality of superposed supports each adapted to support a pile of sheets, means for simultaneously feeding, in a common direction, a sheet from each of such piles, and mechanism for supporting the superposed leading edges of a plurality of such sheets while such sheets are being fed, said mechanism including a table disposed below said pile supports upon which the leading ends of the advancing sheets rest, and means for reciprocating the table along a fixed, generally horizontal path.

4. In a collator, in combination, a plurality of superposed supports each adapted to support a pile of sheets, means for simultaneously feeding, in a common direction, a sheet from each of such piles, and mechanism for supporting the superposed leading edges of a plurality of such sheets while such sheets are being fed, said mechanism including a member disposed below said pile supports upon which the leading ends of the advancing sheets may rest and actuating means for advancing said member and moving said sheet feeding means in sheet feeding direction.

5. The combination set forth in claim 1 in which the pile supports, at the delivery ends thereof, are horizontally offset in the direction in which the sheets are fed therefrom so that the leading edges of sheets simultaneously fed from piles resting thereon are substantially coincident when disposed upon said member.

6. In a collator, in combination, a plurality of superposed supports each adapted to support a pile of sheets, means for simultaneously feeding, in a common direction, a sheet from each of such piles, and mechanism for supporting the superposed leading edges of a plurality of such sheets while such sheets are being fed, said mechanism including a member disposed below said pile supports upon which the leading ends of the advancing sheets may rest and actuating means for advancing said member and moving said sheet feeding means in sheet feeding direction, the said actuating means initiating the motion of the sheet feeding means in sheet feeding direction prior to initiating movement of the sheet supporting member in the same direction.

7. In a collator, in combination, a vertical series of supports for piles of paper, means for simultaneously feeding sheets from said piles, a member disposed below said pile supports having a surface upon which the leading ends of sheets thus fed are received and by which they are supported, and mechanism for actuating said sheet feeding means and said member in timed relationship so that, at about the end of the feeding operation, said member is caused to lift the ends of the sheets resting thereon to a position at which they may be simultaneously grasped.

8. In a collator, in combination, a vertical series of supports for piles of paper, means for simultaneously feeding sheets from said piles, a member having a surface upon which the leading ends of sheets thus fed are received and by which they are supported, said member being mounted for rocking movement about an axis adjacent the support for the lowermost pile, and mechanism for actuating said sheet feeding means and for rocking said member in timed relationship therewith so that, after the sheet ends have been

deposited upon said member, they will be lifted to a position at which they may be simultaneously grasped.

9. In a collator, in combination, a vertical series of paper pile supports which includes upper and lower groups of such supports, a sheet feeding device movable over each pile, a member disposed intermediate said groups of supports and mounted for reciprocation in the direction in which said device moves when feeding sheets, for receiving the leading ends of sheets fed from the uppermost piles of the vertical series, a second member having a surface adapted to receive and support the leading ends of sheets from the lowermost piles of the vertical series, said member being mounted for movement in such manner as to raise and lower its sheet supporting surface, and mechanism for simultaneously actuating said sheet feeding devices, and actuating said members to bring together at a single station the leading edges of all sheets fed at one time.

10. In a collator, in combination, means for supporting a series of piles of paper in superposed relation, the uppermost piles of the series constituting a group and the remaining piles a lower group, and mechanism for simultaneously feeding sheets from said piles and bringing the leading edges thereof to a single station to be grasped, said mechanism including means movable in a generally vertical direction for lifting the leading edges of the sheets fed from the lowermost pile.

11. In a collator, in combination, means for supporting a series of piles of paper in superposed relation, the uppermost piles of the series constituting a group and the remaining piles a lower group, and mechanism for simultaneously feeding sheets from said piles and bringing the lead-

ing edges thereof to a single station to be grasped, said mechanism including means mounted for movement in a generally vertical direction upwardly from an initial station adjacent the lowermost pile supporting means, for elevating the leading ends of sheets of the lower group, and means for actuating said second mentioned means in timed relation to said sheet feeding means.

12. In a collator, in combination, means for supporting a series of piles of paper in superposed relation, the uppermost piles of the series constituting a group and the remaining piles a lower group, and mechanism for simultaneously feeding sheets from said piles and bringing the leading edges thereof to a single station to be grasped, said mechanism including means disposed intermediate said groups of supports for limiting downward movement of the sheets of the upper group and a separate means for elevating the leading ends of the sheets of the lower group.
